FIRE EXTINGUISHER

Teddie C. Mouser, Wasco, Calif.

Application October 4, 1951, Serial No. 249,743

5 Claims. (Cl. 169—27)

1

This invention relates to a fire extinguisher, and more particularly to a fire extinguisher that is actuated by heat or flames of a conflagration.

The object of the invention is to provide a fire extinguisher that includes a mechanism that is actuated upon the outbreak of a fire or conflagration whereby water, or chemicals will be discharged onto the fire to extinguish the fire, the fire extinguisher of the present invention further including an alarm that is actuated when a fire occurs so that persons will be warned of the fire.

Another object of the invention is to provide a fire extinguisher that includes a means for simultaneously extinguishing the fire and sounding an alarm whereby the fire will be automatically extinguished and sleepers or other persons will be notified to thereby provide a fire extinguisher which has double safety features.

Still another object of the invention is to provide a fire extinguisher which will automatically extinguish a fire, the extinguisher of the present invention adapted to be placed in any locality where there is danger of a fire breaking out, the device of the present invention being small and compact and easily refilled and reset.

A further object of the invention is to provide a fire extinguisher which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view of a fire extinguisher, constructed according to the present invention;

Figure 2 is a sectional view taken on the line 2—2 of Figure 1;

Figure 3 is a sectional view taken on the line 3—3 of Figure 2;

Figure 4 is a sectional view taken on the line 4—4 of Figure 2;

Figure 5 is a sectional view taken on the line 5—5 of Figure 2;

Figure 6 is a perspective view of the chemical holding container;

Figure 7 is a plan view of the gasket;

Figure 8 is a plan view of the flammable connector; and

Figure 9 is a perspective view of the flammable connector.

Referring in detail to the drawings, the numeral 20 designates a suitable supporting structure such as a wall, and secured to the supporting

2

structure 20, Figure 2, is a frame 21 which may be fabricated of metal. The frame 21 includes a plurality of spaced parallel legs 22 which are each provided with a flange 23 on one end thereof. Suitable securing elements such as screws 24 extend through the flanges 23 and into engagement with the supporting structure 20 for maintaining the frame 21 connected to the structure 20.

10 Formed integral with the frame 21 or secured thereto is a plurality of end bars 25 and cross pieces 26. A housing 27 is supported on the frame 21, and the housing 27 includes an annular side wall 28 and an end wall 29. Arranged within the housing 27 is a spacer block or ring 32, and extending from the ring 32 is a bracket 31. A bolt 33 serves to connect a dome-shaped bell 34 to the bracket 31 and, as later described in this application, the bell 34 will be sounded upon outbreak of a fire. A plurality of hammers 30 are adapted to be moved into and out of engagement with the inner surface of the bell 34 for sounding the latter.

Extending into the housing 27 is a shaft 35 which is provided with a square portion 36 for a purpose to be later described. A first gear 37 is mounted on the square portion 36, and the gear 37 meshes with an intermediate gear 38 that is rotatably mounted on a pin 39. The gear 38 is arranged in meshing engagement with a gear 40, and the gear 40 is connected to a shaft or pin 41, the pin 41 being secured to a support member 42. The plurality of hammers 30 are supported by or mounted on the member 42. An arm 43 has one end connected to the square portion 36 of the shaft 35, while the other end of the arm 43 is connected to a bushing 44 through which extends the pin 41.

40 A means is provided for selectively causing rotation of the shaft 35 when a fire occurs. This means comprises a spring member 46 which is positioned within the housing 27 and wound about the shaft 35. The inner portion of the spring member 46 is secured to the shaft 35 by a suitable pin 45, while the outer end of the spring 46 is secured to one of the legs 22 by a screw 47.

Arranged on the outer end of the shaft 35 is a sleeve 49, and mounted on the sleeve 49 is a tank 48. The sleeve 49 is provided on its rear or inner end with a ratchet or cam surface 50 which is adapted to engage a pin 51 that extends through the shaft 35. Suitable nuts 52 and 53 are arranged on each end of the shaft 35 for maintaining the parts in their proper assembled relation.

55 A means is provided for preventing the rotation

of the tank 48 until heat from a fire actuates the mechanism. This means comprises a strip of flammable material 54 which may be made of any suitable material such as Celluloid. One end of the Celluloid strip 54 is connected to a bolt and nut assembly 55 that extends from the housing 27, while the other end of the strip 54 is connected to a bolt and nut assembly 56 that extends from the tank 48. When the heat from the fire is sufficient to burn or melt the Celluloid strip 54, the spring member 46 will cause rotation of the shaft 35 and this in turn will cause rotation of the tank 48 whereby the bell 34 will be sounded. At the same time, the tank 48 will be rotated so that the material contained therein will be sprayed onto the fire to extinguish the latter. The strip 54 is provided with suitable holes 57, Figure 9, whereby the bolts 55 and 56 can readily be extended therethrough.

The tank 48 is adapted to hold any desired liquid such as water or other fluid and this liquid is indicated by the letter L. Supported by the tank 48 is a container 58 which is provided with cut-outs 59 whereby the dry chemical C arranged in the container 58 may become intermixed with the liquid L when the tank 48 is being rotated. Extending across the top of the container 58 is an arcuate lid 60 which is provided with a plurality of spaced openings 61 whereby suitable bolts 62 can be extended therethrough. A gasket 63 is interposed between the lid 60 and the annular wall 66 of the tank 48 for insuring that there is a fluid tight seal. The gasket 63 is provided with a large cut-out 64, Figure 7, whereby the major portion of the container 58 can be projected therethrough. Suitable openings 65 are provided for registering with the openings 61 whereby the bolts 62 can extend through the gasket 63. The annular wall 66 of the tank 48 is provided with a plurality of spaced holes or openings 67 whereby the material from the tank 48 will be discharged through the openings 67 and onto the fire to be extinguished.

In use, the tank 58 is filled with a suitable fire extinguishing chemical C and the tank or container 58 is seated in the large tank 48 which is also filled with a fire extinguishing fluid L. Initially the tank 48 is manually rotated to wind up the spring member 46. Then, in the event a fire or conflagration occurs, the flammable strip 54 which has been previously positioned as shown in Figure 2, burns up so that the spring member 46 will cause rotation of the shaft 35. As the shaft rotates, the tank 48 will be rotated due to the pin 51 and ratchet 50. This will cause the liquid L and chemical C to be intermixed due to the provision of the cut-outs 59 and this mixture of fire extinguishing material will be discharged through the openings 67 onto the fire to thereby extinguish the fire. Simultaneously, the hammers 30 will be moved into and out of engagement with the bell 34 so that the bell 34 will be sounded whereby neighbors or other persons will be warned of the fire.

From the foregoing, it is apparent that a fire extinguisher has been provided which will automatically extinguish a fire at the outset. The extinguisher may be placed wherever there is danger of a fire breaking out and it can be made small and compact and will not jam or fail to work. Also, the fire extinguisher of the present invention is simple and can be fastened to a wall or appliance. The bell 34, when sounded, will awaken sleeping persons who might be victims and will also attract nearby neighbors. After

the spring 46 has become unwound, the shaft 35 will quit rotating, but the tank 48 will continue to rotate due to the pin 51 and ratchet 50. Thus, the contents will be continually sprayed onto the fire to be extinguished. The mechanism is first wound and set and then filled with a suitable fire extinguishing liquid. Certain of the outlet openings are designated by the numeral 67', and the openings 67' may be arranged angularly as desired.

I claim:

1. In a fire extinguisher, a frame adapted to be secured to a supporting structure and including a plurality of spaced parallel legs, a cylindrical housing mounted on said legs, a bracket arranged in said housing, a bell secured to said bracket, a plurality of hammers supported for movement into and out of engagement with said bell, a rotatable shaft extending into said housing and gear means operatively coupling said shaft to said hammers for actuating the latter on the turning of the shaft, a spring member positioned in said housing and connected with said shaft for rotating the latter, a sleeve positioned and coupled with said shaft, a tank mounted on said sleeve for holding fire extinguishing fluid, there being openings in said tank for the egress therethrough of material from said tank, and fusible means securing said tank against rotation by the spring member.

2. In a fire extinguisher, a frame adapted to be secured to a supporting structure and including a plurality of spaced parallel legs, a cylindrical housing mounted on said legs, a bracket arranged in said housing, a bell secured to said bracket, a plurality of hammers supported for movement into and out of engagement with said bell, a rotatable shaft extending into said housing and gear means operatively coupling said shaft to said hammers for actuating the latter on the turning of the shaft, a spring member positioned in said housing and connected with said shaft for rotating the latter, a sleeve positioned on and coupled with said shaft, a tank mounted on said sleeve for holding fire extinguishing fluid, there being openings in said tank for the egress therethrough of material from said tank, and fusible means securing said tank against rotation by the spring member.

3. In a fire extinguisher, a frame adapted to be secured to a supporting structure and including a plurality of spaced parallel legs, a cylindrical housing mounted on said legs, a bracket arranged in said housing, a bell secured to said bracket, a plurality of hammers supported for movement into and out of engagement with said bell, a rotatable shaft extending into said housing and gear means operatively coupling said shaft to said hammers for actuating the latter on the turning of the shaft, a spring member positioned in said housing and connected with said shaft for rotating the latter, a sleeve positioned on and coupled with said shaft, a tank mounted on said sleeve for holding fire extinguishing fluid, there being openings in said tank for the egress therethrough of material from said tank, and fusible means securing said tank against rotation by the spring member.

4. In a fire extinguisher, comprising a frame having spaced parallel legs with means at one end thereof for attachment to a supporting surface and transverse members connecting the other ends thereof together, a single shaft rotatably supported by said members and extending at one end into the frame in parallel relation with said legs and having its other end extending outside the frame beyond the transverse members, a bell supported within the frame, rotary striker means supported adjacent to the bell, an operative coupling between the shaft and said striker means for actuating the latter by and upon rotation of the shaft, a coil spring encircling and connected at one end to the shaft and having its other end attached to the frame, a receptacle supported on the said other end of the shaft outside of the frame, said receptacle being adapted to contain a fire extinguishing material, the receptacle being constructed to broadcast said material when rotated by the shaft, and a coupling element between the receptacle

5. In a fire extinguisher, comprising a frame having spaced parallel legs with means at one end thereof for attachment to a supporting surface and transverse members connecting the other ends thereof together, a single shaft rotatably supported by said members and extending at one end into the frame in parallel relation with said legs and having its other end extending outside the frame beyond the transverse members, a bell supported within the frame, rotary striker means supported adjacent to the bell, an operative coupling between the shaft and said striker means for actuating the latter by and upon rotation of the shaft, a coil spring encircling and connected at one end to the shaft and having its other end attached to the frame, a receptacle supported on the said other end of the shaft outside of the frame, said receptacle being adapted to contain a fire extinguishing material, the receptacle being constructed to broadcast said material when rotated by the shaft, and a coupling element between the receptacle

6. In a fire extinguisher, comprising a frame having spaced parallel legs with means at one end thereof for attachment to a supporting surface and transverse members connecting the other ends thereof together, a single shaft rotatably supported by said members and extending at one end into the frame in parallel relation with said legs and having its other end extending outside the frame beyond the transverse members, a bell supported within the frame, rotary striker means supported adjacent to the bell, an operative coupling between the shaft and said striker means for actuating the latter by and upon rotation of the shaft, a coil spring encircling and connected at one end to the shaft and having its other end attached to the frame, a receptacle supported on the said other end of the shaft outside of the frame, said receptacle being adapted to contain a fire extinguishing material, the receptacle being constructed to broadcast said material when rotated by the shaft, and a coupling element between the receptacle

and the frame for holding the receptacle against rotation, said coupling element being of a material readily destroyed by fire.

4. The invention according to claim 3, wherein the said operative coupling between the shaft and striker means comprises a gear train, one of the gears of the train being secured on the inner end of the shaft, the said spring when released under tension functioning to rapidly rotate the receptacle to effect the broadcasting of the contents thereof and to continuously operate said rotary striker.

5. The invention as set forth in claim 3, wherein the support of the receptacle on the shaft comprises a sleeve extending through the receptacle and having the outer end of the shaft received therein, the inner end of the sleeve being formed with a ratchet surface, and a pin

extending transversely through the shaft and adapted for engagement with said ratchet surface, the sleeve being movable axially on the shaft for effecting the engagement of the pin with the ratchet surface or its disengagement therefrom.

TEDDIE C. MOUSER.
